UNITED STATES PATENT OFFICE

2,499,656

SHIFTING DRUM FOR RASCHEL AND
SIMILAR LOOMS

Maurice Eugène Leblanc, Chatou, France, assignor to Société Anonyme des Tissages Lesur, Paris, France, a French company

Application April 14, 1947, Serial No. 741,327
In France August 14, 1946

4 Claims. (Cl. 66—86)

1

Certain mechanical contrivances that are connected with Raschel or similar types of knitting machines, known under the name of shifting drums, allow a sideways movement of the drum along the line of its axis, and thus a variation in the knitting while work is in progress. A comparatively intricate subsidiary piece of gear pushes back the whole of the thread guide rods by one to two centimeters, in such a way that the sideways change of position can be effected in an area of the warp where the link mails are of different height.

The object of our invention is a simple device providing for this performance, and it may be applied to Raschel or similar kinds of knitting machines, when the change of position takes place on zero link mails i. e. smooth link mails. This device may work alone or with any other mechanical feeder of warp.

A description will now be given, as an example without any limiting clause, of a method of carrying the invention into effect.

The figure illustrates an elevation of the device used. As the figure shows, the link mail drum 1 is fitted in a bushing or sleeve 2 that is keyed to the shaft 3 and it may slide freely on this shaft. A spring 4 holds it in place on one side and the other side of the bushing carries a spindle 5 controlled by a bell crank 7 that is pivoted at 8 and carries a spindle 6, that is fixed rigidly with a sliding member 9 that carries a roller 10 running on the link mails 11 of the drum 12, and this drum is fixed on the shaft 13.

The revolving of the shaft 13 is controlled by the crankshaft of the machine on ordinary standard lines.

When travelling from one link mail 11 to the following one of different height, the drum 1 is shifted through a distance amounting to the thickness of one inserted link mail. The tappet-rollers of the thread guide rods, of which the width is exactly the same as that of a link mail travel from one link mail to the following one; and thus the desired pattern may be made. The introduction of a slight change in the warp drum is enough for this purpose, so that the two or three warps tallying with one and the same rod may lie side by side, and tight enough against each other in order that tappet-rollers may travel with ease from any link mail to the other, without any chance of jamming.

The drum 1 as illustrated shows five flanges 14 separate the drum into four grooves (instead of the common standard number of six), each sufficiently wide to take three rows of link mails 15

2

side by side. The link mail chains may be of varying construction; the only hard and fast provision is to have three zero or smooth link mails placed side by side at the spot where the side-shifting of the drum occurs.

The tappet-roller of the thread guide rod slides from one link mail on to the other, and the knitting is thus changed.

What I claim is:

1. In a Raschel or the like knitting machine having a crank shaft, a second shaft, a drum system, said system being shiftable to cause a variation in the knitting of the fabric, said system comprising a sleeve keyed to said second shaft and a drum mounted on said sleeve, a lever pivotally fixed on the frame of said knitting machine for shifting said sleeve longitudinally of its axis, a link-mails carrying drum controlling said lever, and a shaft controlled by said crank shaft for driving said last mentioned drum.
2. In a Raschel or the like knitting machine having a crank shaft, a second shaft, a drum system, said system comprising a sleeve keyed to said second shaft and a drum mounted on said sleeve, a spring urging said sleeve to a predetermined position, a lever pivotally fixed on the frame of said knitting machine for shifting said sleeve longitudinally along its axis, a link-mails carrying drum controlling said lever, a shaft controlled by said crank-shaft for driving said last mentioned drum, a sliding member to actuate said sleeve controlling lever and said last mentioned drum controlling the position of said sliding member.
3. In a Raschel or the like knitting machine having a crank shaft, a second shaft, a drum system, said system comprising a sleeve keyed to said second shaft and a drum mounted on said sleeve, a spring for urging said sleeve into a predetermined position, a lever pivotally fixed on the frame of said knitting machine for shifting said sleeve longitudinally of its axis, a link-mails carrying drum controlling said lever, a shaft controlled by said crank shaft for driving said last mentioned drum, a sliding member to actuate said sleeve controlling lever, the last mentioned drum controlling the position of said sliding member and the first mentioned drum being integral with said sleeve and provided with grooves allowing the passage therein of a plurality of chains with juxtaposed link-mails.
4. In a Raschel or the like knitting machine having a crank shaft, a second shaft, a drum system, said system comprising a sleeve keyed to said second shaft and a drum mounted on

said sleeve, a spring for urging said sleeve into a predetermined position, a lever pivotally fixed on the frame of said knitting machine for shifting said sleeve longitudinally of its axis, a link-mails carrying drum controlling said lever, a shaft controlled by said crank shaft for driving said last mentioned drum, a sliding member to actuate said sleeve controlling lever, the last mentioned drum controlling the position of said sliding member and the first mentioned drum being integral with said sleeve and provided with four grooves allowing the passage therein of a plurality of chains with juxtaposed link-mails.

MAURICE EUGÈNE LEBLANC.
